CALIFORNIA

DEVICE FOR PREVENTING SHORT CIRCUITING FLOW AROUND IMPELLERS

Application filed January 23, 1929. Serial No. 324,443.

My invention relates to the pumping art, and more particularly to a novel impeller and bowl construction for a deep-well turbine pump.

The ordinary type of turbine pump has one or more impellers secured to a pump shaft, each impeller being positioned in an impeller chamber of a pump bowl. The pump bowls are secured together and are positioned below or near the level of the well fluid, while the pump shaft extends upward to the top of the well and is there rotated by a suitable power means.

The rotation of such an impeller draws the well fluid into the central portion thereof and discharges this fluid outward, the centrifugal force thus created acting to impart a high velocity head to the fluid. The major portion of this velocity head is quickly changed into a pressure head as soon as the fluid is discharged from the impeller into a discharge passage formed by the pump bowl. This pressure head in this discharge passage is, of course, much higher than the pressure head of the fluid at the point where this fluid enters the impeller. This differential pressure thus tends to set up a short-circuiting flow of fluid around the lower shroud of the impeller.

The normal direction of this flow is inward and no satisfactory method of eliminating this flow has yet been devised, without resorting to very expensive labyrinth seals. Not only has the preliminary manufacturing cost of such seals been prohibitive, but also these seals are quickly destroyed by the abrasive particles carried by the fluid being pumped.

This short-circuiting flow not only lowers the efficiency of the pump, especially in the smaller sizes where the short-circuiting flow is a material portion of the total capacity, but this flow is also extremely detrimental to the impeller and pump bowl, inasmuch as it invariably carries foreign particles of abrasive matter which collect in the space between the lower shroud and the wall of the pump bowl thereadjacent. The sand pockets thus formed wear the impeller and bowl to such an extent as to require premature replacement.

I have invented a method of preventing

any accumulation of sand below the lower shroud of the impeller, thus preventing wear at this point.

It is an object of this invention to provide a pump construction which prevents the accumulation of abrasive particles adjacent the impeller.

By eliminating this accumulation I have found it possible to use closer running clearances between the impeller and the bowl, thereby decreasing the slippage or short-circuiting flow of pumped fluid around the impeller and thus giving rise to a higher efficiency and making it possible to maintain this efficiency for a much longer period than has been heretofore possible.

In my pump construction, I provide an auxiliary pump means for reversing the normal flow of well fluid through the space between the impeller bowl and the lower shroud of the impeller so that any flow which takes place parallels the flow through the main passage of the impeller.

It is an object of this invention to provide a pump structure in which the well fluid moving through the space between the lower impeller and the pump bowl moves in the same general direction as does the main body of fluid passing through the impeller. In other words, instead of a short-circuiting flow, the pump of my invention provides parallel paths through which the fluid may pass through the impeller chamber, one of these paths being the normal path through the impeller and the other being the path between the impeller and the pump bowl.

Still another object of this invention is to provide a pump construction in which these desirable results are obtained without the use of any extra parts, thus making it possible to achieve these added objects without an excessive increase in cost of the pump.

Further objects and advantages of my invention will be evident from the detailed description, and from the subsequent statements of the results attained by the use of my pump construction in comparison with other pump constructions.

Referring to the drawings in which I have

illustrated a preferred embodiment of my invention,

Fig. 1 is a utility view, partially in section, illustrating one type of pump in which my invention is particularly applicable.

Fig. 2 is a cross-sectional view illustrating the details of my invention.

Fig. 3 is a sectional view taken on the line 3—3 of Fig. 2.

10 Fig. 4 is a graph on which a curve of pressure against output is plotted.

Referring particularly to Fig. 1, I have illustrated a deep-well turbine pump comprising a pump section 10, positioned in the lower end of a well 11, and inside a well-casing 12. The pump section is supported by a suitable discharge tube 13 which extends upward to the surface of the ground and is connected to a pump head 14. A shaft 15 extends from the pump section 10 upward inside the discharge tube and is rotated by a means 16. The pump section 10 is formed of a plurality of pump bowls 19 suitably secured together.

25 The details of these pump bowls may best be understood by reference to Fig. 2 wherein two of the pump bowls 19 are illustrated as being connected together by bolts 20 passing through an upper flange 21 of the lower bowl 30 and being threadedly received into the lower walls of the pump bowl thereabove. An impeller chamber 22 is formed in each of the 35 pump bowls, a lower portion of this impeller chamber being defined by an upper wall 23 of the pump bowl 19 immediately therebelow. Each of the impeller chambers 22 communicates between an intake passage 24 and a discharge passage 25, these passages being formed in a pump bowl structure 26 which 40 comprises the different pump bowls 19.

Positioned in each impeller chamber 22 is an impeller 30 having a hub 31 which is secured to the shaft 15 by any suitable means such as a key 32. The lower portion or eye 33 45 of the impeller extends into a bore 34 in a manner to leave a primary clearance space 35 therebetween, this clearance space being ordinarily small.

Formed through the impeller is an impeller 50 passage 36 which has vanes 37 therein. The passage 36 has an inlet port 38 in communication with the intake passage 34 and has an outlet port 39 in communication with the discharge passage 25.

55 When the shaft 15 is rotated, each of the impellers draws well fluid upward through the adjacent intake passage and discharges this fluid into the adjacent discharge passage 25. This particular type of centrifugal impeller has the property of centrifugally discharging the well fluid from the outlet port 39 at a relatively high total head. At the point of discharge from the impeller, this total head is divided into a high velocity 60 head and a rather low pressure head. As soon 65

as this fluid reaches the discharge passage 25 the pressure head becomes high and the velocity head lowers a corresponding amount. Thus, the pressure in the discharge passage 25 invariably higher than the pressure in the intake passage 24, and this differential pressure has heretofore invariably set up a short-circuiting flow around the lower shroud 42 of the impeller 30 in a direction indicated by the dotted arrow 43. This flow takes place through an auxiliary chamber 44 formed between the lower shroud 42 and the upper wall 23. Due to the fact that the velocity head of the fluid changes into a high pressure head very soon after entering the discharge passage 25, any abrasive particles which are carried by the fluid passing through the conventional type of pump are allowed to drop into the chamber 44. Heretofore great difficulty has been encountered due to these abrasive particles collecting in the chamber 44 and wearing the upper wall 23, and especially the lower shroud 42 of the impeller.

20 Various types of labyrinth packing have been devised for decreasing this short-circuiting flow, but it has been impossible to eliminate this short-circuiting flow. Furthermore, these packings are invariably placed adjacent the eye of the impeller, thus 25 allowing an accumulation of sand below this impeller even though the short-circuiting flow is decreased.

30 My invention comprises the formation of a skirt 47 on the outer portion of the lower shroud 42, this skirt extending in close proximity to a cylindrical wall 48 of the impeller chamber 22. A secondary clearance space 49 is formed therebetween, this clearance space 35 ordinarily being in the neighborhood of several thousandths of an inch. Formed through the skirt 47 are one or more upwardly inclined openings 50. As best shown in Fig. 2, the inner ends of these openings communicate with the auxiliary chamber 44, while the outer ends of these openings communicate with the clearance space 49. The openings 50 act as an auxiliary pumping means tending to centrifugally discharge any liquid in the chamber 44 therethrough and into the clearance space 49.

35 The theory of operation of my invention may best be understood by reference to Fig. 4 which illustrates a coordinate system having as ordinates the total head developed per stage, and as abscissa the output in gallons.

40 A typical test curve 55 has been plotted, this curve having a decided droop indicating that as the output of the impeller is increased, the total head developed by this impeller decreases. In fact, with the particular impeller tested in securing the information disclosed in Fig. 4, the total head per stage under no output was 60 feet. As the output of the impeller increases, or, in other words, as more fluid passed through the passage 36 45

thereof, the total head per stage dropped. When the output was 900 gallons per minute, the total head was in the neighborhood of 36 feet instead of 60 feet as previously.

5 It is well established that the total head developed by an impeller is a function of, and nearly proportional to, the maximum radius of the passage 36 therein. In other words, with a given output, the total head developed by an impeller is proportional to the distance 10 between the center of rotation of the shaft 15 and the mouth of the outlet port 39.

In Fig. 2 I have illustrated an impeller, the mouth of the outlet port 39 of which is not parallel to the axis of rotation, but instead converges upward, so that the upper portion 52 of this mouth is closer to the axis of the shaft 15 than is the lower portion 53 of this mouth. With this particular type of 20 impeller, the total head developed thereby with a given output is substantially proportional to the mean distance between the axis of rotation of the shaft and the portions 52 and 53 of the mouth of the outlet port 39.

25 The outer periphery of the skirt 47 is positioned at a radius which is greater than this mean difference, and it therefore follows that the pressure developed by the centrifugal force of the fluid in the openings 50 is always 30 greater than the pressure developed in the passage 36 of the impeller, even though the flow through this passage 36 is reduced to substantially zero. In other words, the impeller 30 at zero output might develop a head of 60 feet in the passage 36, but the head developed in the openings 50 would exceed 35 this value by several feet due to the fact that the mouths of these openings are at a greater radial distance from the shaft than the mean 40 distance between the shaft and the portions 52 and 53. This causes a flow of fluid upward through the clearance space 35 and into the chamber 44, this fluid being discharged 45 through the openings 50 and into the clearance space 49.

It should be understood that the volume 50 of fluid passing through the openings 50 is at all times very small due to the proximity of the cylindrical wall 48 to the mouths of the openings 50, and that therefore the total head developed by the openings 50 is not materially decreased by a large output therethrough. In other words, the pumping means formed by the openings 50 would follow a 55 curve 59 shown in Fig. 4, this curve lying above the curve 55 and extending only a very short distance along the abscissa scale. When the output of the impeller increases, the total head developed thereby also decreases, thus accentuating the difference in 60 values of head developed by the passage 36 and the openings 50.

To insure that the flow of fluid passing 65 through the openings 50 be directed upward into the discharge passage 25 rather than

being short-circuited around the lower edge of the skirt 47, I incline these openings upward, as best indicated in Fig. 2. Furthermore, the mouth of each opening 50 is only a small distance below a ledge 60 defining the upper end of the cylindrical wall 48, while the portion of the periphery of the skirt 47 below the mouth of the openings 50 extends a material distance downward in close proximity to the cylindrical wall 48.

70 The clearance space 49 in effect acts as a sealing means, due to the very small width of this space, this sealing means being ordinarily filled with a fluid. The sealing area below the mouth of the openings 50 is much 80 larger, however, than that above the mouth of the openings 50, inasmuch as these openings are positioned as heretofore described. There is thus very little resistance to flow 85 upward through the clearance space 49 from the openings 50, but a material resistance to flow downward through the clearance space 49 from the openings 50. This effect also aids in preventing a short-circuiting flow 90 around the lower edge of the skirt 47.

95 It should thus be apparent that any fluid entering the auxiliary chamber 44 will be discharged through the openings 50 irrespective of the amount of flow through the passages 36 of the impeller. It should further be apparent that in my invention the direction of flow through the chamber 44 is reversed from the ordinary direction of flow. In other words, the pumping means draws the fluid 100 through this chamber in a direction indicated by the arrow 62.

Furthermore, by making the clearance space 49 extremely narrow, this clearance space restricts the flow of fluid through the chamber 44, thus insuring a low velocity in 105 the clearance space 35. The differential velocity which exists between the streams of fluid passing through the intake passage 24 and the clearance space 35 is usually greater than ten feet per second. In fact, the velocity of the fluid in the clearance space 35 is so low that abrasive particles will not be raised thereby, but will gravitate therefrom and into the larger and faster fluid stream passing through the intake passage 24. This action is important to this invention and prevents any material wear between the skirt 47 and the cylindrical wall 48. It is thus impossible for any abrasive particles to accumulate between the upper wall 23 and the lower shroud of the impeller and the wear which heretofore took place due to this accumulation of abrasive particles is entirely 110 eliminated.

115 The simplicity of the means for accomplishing these desirable results should be apparent. No additional working parts over those ordinarily used are needed in building this type of pump construction, and only very little 120

more machine work is required on the pump bowls and impeller.

My invention finds various applications outside of the deep-well turbine art, and I am thus not limited to this particular art.

5 I claim as my invention:

1. In a turbine pump, the combination of: an impeller having an inlet port and an outlet port therein; a pump bowl structure in 10 which said impeller rotates, there being an auxiliary chamber between said impeller and said pump bowl structure, said structure providing an intake passage and a discharge passage communicating respectively with 15 said inlet and outlet ports; and an auxiliary pump means for drawing fluid into said auxiliary chamber from said intake passage and discharging it into said discharge passage.

2. In a turbine pump, the combination of: 20 a pump bowl structure providing an impeller chamber; an impeller having upper and lower shrouds and being adapted to rotate in said impeller chamber; and means for setting up between said lower shroud and said pump bowl structure a flow of well fluid which parallels the flow of said well fluid through said impeller.

3. In a turbine pump, the combination of: 30 an impeller having an inlet port and an outlet port therein; a pump bowl structure in which said impeller rotates, there being an auxiliary chamber between said impeller and said pump bowl structure, said structure providing an intake passage and a discharge 35 passage communicating respectively with said inlet and outlet ports; and a skirt on said impeller and having an opening therein acting to centrifugally discharge fluid from said auxiliary chamber into said discharge 40 passage.

4. In a turbine pump, the combination of: 45 an impeller having an inlet port and an outlet port therein; a pump bowl structure in which said impeller rotates, there being an auxiliary chamber between said impeller and said pump bowl structure, said structure providing an intake passage and a discharge 50 passage communicating respectively with said inlet and outlet ports; an auxiliary pump means for drawing fluid into said auxiliary chamber from said intake passage and discharging it into said discharge passage; and means for restricting the flow of fluid pumped by said auxiliary pump means so that the 55 pressure developed thereby is always greater than the pressure set up in said outlet port of said impeller.

5. In a turbine pump, the combination of: 60 an impeller having an inlet port and an outlet port therein; a pump bowl structure in which said impeller rotates, there being an auxiliary chamber between said impeller and said pump bowl structure, said structure providing an intake passage and a discharge 65

passage communicating respectively with said inlet and outlet ports; a skirt on said impeller and having an opening therein acting to centrifugally discharge fluid from said auxiliary chamber into said discharge passage; and means for maintaining the flow of fluid through said opening substantially constant.

6. In a turbine pump, the combination of: 70 a pump bowl structure defining an impeller chamber bounded on one side by a cylindrical wall; an impeller adapted to rotate in said impeller chamber; a skirt on said impeller rotating in close proximity to but spaced from said wall; and an opening 75 through said skirt and adapted to centrifugally discharge fluid between said skirt and said cylindrical wall.

7. In a turbine pump, the combination of: 80 a pump bowl structure defining an impeller chamber bounded on one side by a cylindrical wall; an impeller adapted to rotate in said impeller chamber; a skirt on said impeller rotating in close proximity to said wall; an opening through said skirt and adapted to 85 centrifugally discharge fluid between said skirt and said cylindrical wall; and a settling space through which said fluid must 90 pass before reaching said opening.

8. A combination as defined in claim 6 in 95 which said impeller has an outlet port discharging into a discharge passage of said pump bowl structure and in which said opening is inclined in a manner to force said fluid into said discharge passage.

9. In a turbine pump, the combination of: 100 a pump bowl structure providing an impeller chamber, a portion of which is defined by a bore in said structure and a cylindrical wall concentric with said bore; an impeller adapted to rotate in said chamber, said impeller having an eye extending into said bore in a manner to form a primary clearance space therebetween communicating with an intake passage and with an auxiliary chamber 105 formed between said impeller and said pump bowl structure; and a skirt formed on the periphery of said impeller and rotating adjacent said cylindrical wall in a manner to form a secondary clearance space therebetween communicating with said auxiliary chamber 110 and with a discharge passage, said skirt providing an opening therethrough communicating with said auxiliary chamber and said secondary clearance space.

10. A combination as defined in claim 9 in which the mouth of said opening opens on said secondary clearance space at a point near that end of said secondary clearance space which communicates with said discharge passage.

11. A combination as defined in claim 9 in which said opening is inclined toward that end of said secondary clearance space which communicates with said discharge passage.

12. A combination as defined in claim 9 in which said primary clearance space is substantially vertical and in which said secondary clearance space limits the velocity of said fluid in said primary clearance space so that abrasive particles carried by said fluid may settle therefrom before the fluid enters said auxiliary chamber.

13. In a turbine pump, the combination of:
10 walls defining an impeller chamber communicating with an intake and a discharge passage; an impeller rotating in said impeller chamber to pump a fluid containing abrasive particles from said intake passage
15 through said discharge passage, said impeller providing an eye rotating in close proximity to said walls to define an upright clearance space, said fluid moving through said eye and having a velocity adjacent the mouth
20 of said clearance space to carry said abrasive particles upward therewith; and means for setting up an upward flow of said fluid through said clearance space of insufficient velocity to raise said abrasive particles there-
25 with.

In testimony whereof, I have hereunto set my hand at Los Angeles, California, this 18th day of January, 1929.

ARTHUR R. WEIS.
